UNITED STATES PATENT OFFICE.

ULYSSES S. GRANT HINTON, OF MONTEREY PARK, CALIFORNIA.

AUTOMATIC AIR CONTROL.

1,330,265.

Specification of Letters Patent. Patented Feb. 10, 1920.

Application filed March 3, 1917. Serial No. 152,291.

To all whom it may concern:

Be it known that I, ULYSSES S. GRANT HINTON, a citizen of the United States, residing at Monterey Park, in the county of 5 Los Angeles, State of California, have invented new and useful Improvements in Automatic Air Control, of which the following is a specification.

This invention relates to gas savers for 10 automobiles and the like; and it is an object of this invention to provide a simple and inexpensive device which may be easily applied to a carbureter and which, when applied, has the function of greatly increasing 15 the efficiency of the carbureter and the engine to which it is attached.

It is further an object of this invention to provide a device which, when applied to a carbureter, will always be uniform in action 20 and will not be affected in action by variations in the size of the parts in which it is placed. For instance, in some gas savers, the application of the saver to the carbureter is liable to change the interrelation 25 of the parts of the gas saver, so that the gas saver does not act in a normal and uniform manner; and it is a specific object of my invention to overcome this difficulty.

It is also an object of my invention to provide, in such a simple device as herein described, a means for taking care of back 30 fires through the carbureter. This I do in a very simple manner, as hereinafter specified.

35 In the following specifications, I describe a preferred and specific form of device embodying my invention; and reference is had for this purpose to the accompanying drawings in which Figure 1 is a side elevation 40 of a carbureter, showing my gas saver in operative position, certain parts being shown in section; Fig. 2 is an enlarged longitudinal section of my gas saver; Fig. 3 is an end view thereof taken as indicated by line 3—3 45 on Fig. 2; and Fig. 4 is a section taken as indicated by line 4—4 on Fig. 2.

In the drawings the numeral 10 designates 50 any ordinary carbureter having its air intake at 11, which may be controlled by air throttle 12. In one common form of carbureter this air intake may be provided with a tube 13, which extends outwardly and upwardly, having a part 14 at its upper end adapted to be clamped against the exhaust

55 manifold of the engine, for the purpose of heating the air entering the carbureter. I make my gas saver 15 to fit into the inner end of this tube 13. My gas saver comprises a cylindrical shell 16 with a preferably conical enlargement 16^a on one end. 60 This enlargement is of such dimensions as to cause the shell to be fitted tightly and snugly into any tube 13, taking care of any small variations in the size of the tube; and doing this without the necessity of changing 65 the effective diameter of the shell 16. In the other end of the shell I mount the pivoted valve 17. This valve 17 is pivotally mounted upon a suitable transverse pivot pin 18, ears 19 being turned up on the 70 periphery of the valve to engage the pivot pin 18. Pivot pin 18 is set in shell 16 by providing indentations in the wall of the shell, as shown at 20, and passing the pivot pin through apertures in the indented 75 portions.

Valve 17 is preferably made of stamped sheet metal and is substantially circular; and has a hook 21 stamped out of itself and adapted to be engaged by the end of the 80 valve closing spring 22; the other end of the valve closing spring being hooked around a small projection 23 at the swedged end of the shell. The valve normally stands in the position shown in the drawings; and 85 its upper edge presses against a stop 24 formed by the inward bending of a small portion of the end of the shell; the spring 22 holding the valve normally against this stop. The lower part of the valve, being 90 that part below the pivot pin 18, is bent outwardly, as shown at 17^a in Fig. 2, so that this part stands in a diagonal position pointing diagonally outward toward the direction 95 from which the air comes, this direction being indicated by the arrow in Fig. 2. Any back fire which occurs comes from the direction of the carbureter, and impinges upon the valve in the direction opposite to that indicated on Fig. 2.

100 It will be noted that the shell and the valve being both circular, there is a definite and uniform open space around the upper part of the valve, between the upper part of the valve and the shell; but the bending of 105 the lower part 17^a of the valve, to a diagonal position, makes a somewhat wider opening between the lower part of the valve and the

shell; that is, between the shell and that part of the valve which is below the pivot pin 18. By reference to the drawings, it will be seen that the space at 25 is wider than the space 5 at 26. This widened space, and the diagonal position of the parts 17^a, play an important function; and it will be noted that, for the purpose of this function, it is important that the relation of the valve to the 10 shell be fixed and not be variable. When the engine is running at low speed, sufficient air is drawn through the spaces around the valve to supply the engine; when the engine runs at a higher speed, or the throttle is 15 opened to admit more air to the engine, then the valve is proportionately opened against the action of spring 22; the strength and tension of this spring being determined and set in accordance with the requirements of 20 the carbureter and engine. Now, when a back fire occurs, the back rush of gases tends to immediately seek the path of least resistance to flow; and the stream of outrushing gases is thus directed to the wider opening 25 at 25 under the diagonal part 17^a. The effect of this construction and operation has been shown in practice to sufficiently relieve the back pressure.

The moving parts are preferably of light 30 weight, so as to respond quickly, and I find that my gas saver is not only very efficient in action, due to the fact of proper proportioning and unchangeable relation between the shell and the valve; but is also very effective to release a back fire, due to the action 35 just described.

Having described a preferred form of my invention, I claim:

1. A gas saver for a carbureter adapted 40 to be attached to the air intake of the carbureter; embodying an exterior shell, a valve pivoted transversely across the shell and bearing a certain definite and unchangeable relation to the shell, and spring means to 45 normally hold said valve closed, the body of said valve extending substantially transversely across the shell, and a part of said valve on one side of its pivot extending diagonally outwardly toward the outer end of the shell and spaced from the shell wall, whereby back fire pressure is relieved.

2. A gas saver for a carbureter adapted 50 to be attached to the air intake of the carbureter; embodying an exterior shell, a valve pivoted transversely across the shell and bearing a certain definite and unchangeable relation to the shell, and spring means to 55 normally hold said valve closed, the body of said valve extending substantially transversely across the shell, and a part of said valve on one side of its pivot, extending diagonally outwardly toward the outer end of the shell, there being a fixed open space between the body of the valve and the shell, 60 and there being a wider fixed open space

between the diagonally extending portion of the valve and the shell, whereby back fire pressure is relieved.

3. A gas saver for a carbureter adapted to be attached to the air intake of the carbureter comprising an attaching member; an exterior shell adapted to be inserted into the attaching member, a valve pivoted transversely across the shell and bearing a certain definite and unchangeable relation to 70 the shell, and spring means to normally hold said valve closed, the shell having means formed at the end adapted to retain the shell in the attaching member subsequent to insertion therein without changing the definite 75 relation of the shell to the valve.

4. A gas saver for a carbureter adapted to be attached to the air intake of the carbureter; embodying an exterior shell, a valve pivoted transversely across the shell and bearing a certain definite and unchangeable relation to the shell, and spring means to normally hold said valve closed, the body of said valve extending substantially transversely across the shell, and a part of said 85 valve on one side of its pivot, extending diagonally outwardly toward the outer end of the shell, there being a fixed open space between the body of the valve and the shell, and there being a wider fixed open space between the diagonally extending portion of the valve and the shell whereby back-fire 90 pressure is relieved, the shell having an enlarged end for fitting the shell into the air intake without changing the definite relation 95 of the shell to the valve.

5. A gas saver for a carbureter adapted to be attached to the air intake of the carbureter; embodying an exterior shell, a valve pivoted transversely across the shell, and spring means to normally hold said valve in closed position across the shell, the body of said valve extending substantially transversely across the shell, and having an opening movement inwardly against the action 105 of said spring, and a part of said valve on one side of its pivot extending diagonally outwardly toward the outer end of the shell and spaced from the shell, whereby back fire 110 pressure is relieved.

6. A gas saver for a carbureter adapted to be connected to the air intake thereof; embodying an exterior shell, a valve pivoted transversely across the shell, and spring means to normally hold the valve in closed 115 position, the valve lying on both sides of its pivot and the pivot being closer to one edge of the valve than to the other, the valve being shaped so as to leave a larger normally open space between the shell and that edge 120 of the valve closer to the pivot than between the shell and the other edge of the valve, whereby back fire pressure is relieved.

7. A gas saver for carbureters having an air intake pipe, a shell adapted to be insert- 125

ed in the pipe, a valve pivoted transversely across the shell and bearing in its normal position a certain definite and unchangeable relation to the shell, means normally to hold the valve closed, and one end of the shell being conically enlarged to fit into and hold the shell in air intake pipes of different sizes

without changing the definite relation of the shell to the valve.

In witness that I claim the foregoing I 10 have hereunto subscribed my name this 26th day of February, 1917.

U. S. GRANT HINTON.
